ABSTRACT

A plurality of inverting circuits and/or clipper circuits are connected to a counting circuit to synthesize the output signal of the counting circuit. The synthesized output signal becomes a desired rhythm.

AUTOMATIC RHYTHM PERFORMANCE DEVICE

BACKGROUND OF THE INVENTION

This invention relates to an automatic rhythm performance device and, more particularly, to a device in which any desired rhythm can be obtained by synthesizing the rectangular waveforms of output signals from a plurality of counting circuits into inverting circuits with resistant circuit networks and/or into clipper circuit with resistant circuit networks.

In a prior art rhythm performance device using electronic system, any desired type of pulse train is obtained by combining sequential pulses from counter circuits combined to a tempo oscillator to make a ring circuit, by picking up pulses necessary to make the pulse train and by synthesizing the pulses. According to this device, the number of the counter circuits becomes equal to the number of the minimum units of the rhythm to be obtained so that a large number of constitutional elements are required to make up the device.

In another prior art rhythm performance device using electronic system, any desired type of pulse train is obtained by connecting diode matrix circuits to counter circuits and, in this matrix circuits, output pulses obtained by differentiating directly the output signal of the counter circuits are synthesized with output pulses of square waveform obtained from the counter circuits without losing the DC component of the pulses. According to this device, the number of the counter circuits are made less than that of the first mentioned prior art device.

SUMMARY OF THE INVENTION

In this invention, the output signals from a counting circuit is synthesized by means of resistant circuit networks provided at the first stage of inverting circuits and/or clipper circuits and, therefor, an automatic rhythm performance device is obtained with less constitutional elements than those in any prior art device.

It is an object of this invention to provide an automatic rhythm performance device in which a desired rhythm is obtained by synthesizing the square waveforms of output signals from a counting circuit in inverting circuits, in clipper circuits and/or in a combination circuits thereof.

It is another object of this invention to provide an automatic rhythm performance device in which resistant circuit networks are used in place of any prior art diode matrix so that the cost becomes less for the simplicity of the resistant circuit networks which use principally resistances.

BRIEF DESCRIPTION OF THE DRAWING

FIG. 1 shows the block diagram of an embodiment of the automatic rhythm performance device provided in accordance with this invention.

FIG. 2 shows the output waveforms of the counter circuits shown in FIG. 1,

FIG. 3 is the inverting circuit of this invention,

FIG. 4 is the clipper circuits of this invention,

FIG. 5 shows the pulse waveforms which explain the operation of the inverting circuits shown in FIG. 3, and

FIG. 6 shows the pulse waveforms which explain the operation of the clipper circuits shown in FIG. 4.

DESCRIPTION OF THE PREFERRED EMBODIMENT

In FIG. 1, a variable frequency tempo oscillator 1 is connected to a counter circuit 2 comprising a ternary counter circuit 3 and flip-flop circuits 4 to 7 connected in series. The tempo oscillator can be implemented employing a pulse generator and frequency control as shown in U.S. Pat. No. 3,358,068 to R. H. Campbell, Jr. and hereby incorporated by reference. The outputs of the flip-flop circuits are connected to a plurality of resistant circuit networks 8. The output of the resistant circuit networks connected to a plurality of inverting rectifiers 11 through differentiation circuits 9 or to a plurality

of differentiation circuits 12 through clippers 10. The outputs of the inverting rectifiers and the differentiation circuits are connected to rhythm selectors 13, the output therefrom being connected to a plurality of percussive sound generators 14.

5 The outputs of the percussive sound generators are connected to a speaker 16 through an amplifier 15. An inverting circuit I is comprised of resistant circuit networks 8, differentiation circuits 9 and inverting rectifiers 11 and a clipper circuit II is comprised of resistant circuit networks 8, clippers 10 and differentiation circuits 12.

10 As shown in detail in FIG. 3, the inverting circuit I is comprised of the following elements:

15 Input terminals 17, 18, 19 and 20 are connected respectively to one end of resistances R₁, R₂, R₃ and R₄. The other ends of the resistances R₁, R₂, R₃ and R₄ are connected to a point P₁ and the point P₁ is further connected to one end of a resistance R₅ and to one end of a capacitance C₁. The other end of the resistance R₅ is grounded. The other end of the capacitance C₁ is connected to a point P₂. The point P₂ is connected to one end of a resistance R₆ and to one end of the primary winding of a transformer T₁. The other end of the resistance R₆ is grounded. The other end of the primary winding is also grounded. To the secondary winding of the transformer T₁ the cathodes of diodes D₁ and D₂ are connected and the center tap of the transformer T₁ is grounded. The anodes of the two diodes are connected to an output terminal 21.

20 As shown in detail in FIG. 4, the clipper circuit II is comprised of the following elements:

25 Input terminals 22, 23 and 24 are connected respectively to one end of resistances R₇, R₈ and R₉. The other ends of the resistances R₇, R₈, and R₉ are connected to a point P₃ and the point P₃ is further connected to one end of a resistance R₁₀ and to the anode of a diode D₃. The other end of the resistance R₁₀ is grounded and the cathode of the diode D₃ is connected to a reference voltage E_r. The point P₃ is connected to one end of a capacitance C₂ through a point P₄. The other end of the capacitance C₂ is connected to a point P₅. The point P₅ is connected to one end of a resistance R₁₁ and to the cathode of a diode D₄. The anode of the diode D₄ is connected to an output terminal 25.

30 The diode D₃ serves as a clipper at a proper level to the stepped waves which are synthesized by resistant circuit network 8 in order to obtain a plurality of rectangular waveform necessary to constitute a desired rhythm. The diode D₄ serves as a buffer diode to minimize the effects of other circuit. The reference voltage E_r provides a voltage level at which clipping is effected.

35 The number of the inverting circuit I and the clipper circuit II is to be the same as the number of the pulse trains which constitute the rhythm desired. However, as the inverting circuit I and the clipper circuit II can be used in duplicate in constituting the rhythm, the number of the two circuits is not necessarily the same as the number of the pulse trains. For example, even though five circuits are required to constitute Bossa Nova, four circuits are required to constitute tangos and 10 circuits are required to constitute waltz, all the 19 circuits are not required in order to play the three rhythms.

40 In FIG. 2, the waveform T represents the output pulses from tempo oscillator 1 shown in FIG. 1. The numbers 1, 2, 3 .... denote the order of the pulse trains in tempo oscillator 1. The waveforms A, A'; B, B'; C, C'; D, D' and E, E' represent, respectively the outputs from ternary counter circuits 3; flip-flop 4; flip-flop 5; flip-flop 6 and flip-flop 7.

45 The operations of the inverting circuit I and the clipper circuit II are explained in the following to which the output signals necessary to constitute the desired rhythm applied out of the output signals of the counter circuit 2.

50 1. When the output signals are applied to the inverting circuit I;

55 The output waveforms B, C, D' and E' out of counter circuit 2 are applied to the input terminals of resistant circuit network 8 of the inverting circuit I_a as shown in FIG. 1, more particularly, to input terminals 17 to 20 as shown in

FIG. 3. The output waveforms applied provide a staired waveform F as shown in FIG. 5 at point P₁ in FIG. 3 through resistances R₁ to R₄ in the same figure. As the waveform F is differentiated by differentiation circuit 9 in FIG. 1, which is comprised of capacitance C₁ and resistance 6 shown in FIG. 3, a pulse train of a waveform G as shown in FIG. 5 is provided at point P₂ in FIG. 3. The pulse train is inverted and rectified as a pulse train of waveform H as shown in FIG. 5, which has negative pulses only, through inverting rectifier 11 in FIG. 1, more particularly through the transformer T₁ and the diodes D₁ and D₂.

The pulse train thus obtained has a number of negative pulses, such as 4, 10, 13, 16, 22 and 25, as shown in FIG. 5.

2. When the output signals are applied to the clipper Circuit II:

The output waveforms A, C' and D' out of counter circuit 2 are applied to the input terminals of resistant circuit network 8 of the clipper circuit II_a as shown in FIG. 1, more particularly, to input terminals 22 to 24 as shown in FIG. 4. The output waveforms applied provide a staired waveform I as shown in FIG. 6 at point P₃ in FIG. 4 through resistances R₇ to R₉ in the same figure. As the waveform I is clipped by clipper 10 with a voltage level of the reference voltage E₁ in FIG. 1, which is comprised of diode D₃ shown in FIG. 4, a pulse train of a waveform J as shown in FIG. 6 is provided at point P₄ in FIG. 4. The pulse train is differentiated by differentiation circuit 12 in FIG. 1, which is comprised of capacitance C₂ and resistance 11 shown in FIG. 4 to become a pulse train of a waveform K as shown in FIG. 6. The pulse train is further rectified by diode D₄ shown in FIG. 4 to finally become a pulse train of a waveform L as shown in FIG. 6.

The pulse train thus obtained has a number of negative pulses, such as 2, 5, 26 and 29, as shown in FIG. 6.

When the inverting circuit I and the clipper circuit II are actually used to obtain an automatic rhythm performance device, one of the two circuits are used in plural or the two circuits are used in combination, in other words the n inverting circuits I_a to I_n and the m clipper circuits II_a to II_m are utilized.

As explained above, in this invention a number of pulse trains are selected out of the pulse trains H, H_b, H_c..... H_n produced by the inverting circuits I_a, I_b, I_c..... I_n, respectively and out of the pulse trains L, L_b, L_c..... L_m produced by the

clipper circuits II_a, II_b, II_c..... II_m and are synthesized to obtain a desired rhythm.

More particularly, in FIG. 1, it is shown that pulse trains H, H_b, L and L_b are connected to rhythm selector 13a. Rhythm selectors 13b, 13c . . . are similarly connected to a number of pulse trains specifically selected. When rhythm selector 13a is to be actuated to obtain a rhythm desired, such as tangos, the outputs of rhythm selector 13a are applied to a number of percussive sound generators 14a, 14b, 14c and 14d. The output of each of the four percussive sound generators provides, a respective music, such as, bongo music, maracas music, cymbal music and snare drum music. These outputs from the percussive sound generators are synthesized in amplifier 15 and applied to speaker 16 to generate a rhythm, tangos.

When rhythm selector 13b is to be actuated to obtain a rhythm desired, such as waltz, the outputs of the rhythm selector are applied to the percussive sound generators used to provide the rhythm waltz to generate a rhythm, waltz, from the speaker. In this manner, rhythm selector 13c etc. are actuated to obtain actuated to obtain a rhythm, such as mambo, Bossa Nova, trot.

If the circuits shown in FIG. 1 is prepared by means of printed resistance and capacitance the circuits can be naturally made in a mass-production system to make the cost of the rhythm performance device cheaper and this means a remarkable improvement in the industrial field concerned.

What is claimed is;

1. An automatic rhythm performance device comprised of: a counter circuit connected to a tempo oscillator having variable frequency; inverting circuits including serially connected resistant circuit networks, differentiation circuits and inverting rectifiers, said inverting circuits being connected to said counter circuit; clipper circuits including serially connected resistant circuit networks, clippers and differentiation circuits, said clipper circuits being also connected to said counter circuit; rhythm selectors connected to predetermined circuits of said inverting circuits and said clipper circuits; percussive sound generators connected to said rhythm selectors and a speaker whereby the output signals out of said counting circuit is synthesized by means of said inverting circuits and said clipper circuits to provide a pulse train of a desired rhythm and to actuate said percussive sound generator by said pulse train.
